SINGLE POINT IGNITION

Ernst Witzel, Milwaukee, Wis., assignor to Milwaukee Gas Specialty Company, Milwaukee, Wis., a corporation of Wisconsin

Application April 30, 1947, Serial No. 744,905

15 Claims. (Cl. 158—124)

1

This invention relates, in general, to ignition systems and has particular relation to an improved single point ignition system for fuel burners.

While the particular embodiment of the invention which I shall describe hereinafter in connection with the drawings is a single point ignition system adapted for use with domestic gas ranges, it is to be understood that the invention is not limited to such use, but may be employed for all similar purposes, for example, in connection with various commercial forms of apparatus having a baking oven burner, broiler oven burner or other burner remotely located relative to the pilot burner.

In the usual domestic gas range, the pilot burner is in the form of a single, constantly burning pilot burner located in juxtaposition to the top burners at the upper part of the range, and the baking oven, broiler or like burners are located in the lower part of the range. Although the top burners are usually provided with a constantly burning pilot burner for lighting the same, at the present time a match is usually employed for lighting the baking oven, broiler or like burners. The stooping and hazards of lighting an oven burner or the like with a match are well known in the art.

In my copending application, Serial No. 738,412, filed March 31, 1947, I provide an improved system of flash tubes and intermediate pilot burner means for assuring ignition of a pilot burner in juxtaposition to the oven or like burner from a constantly burning top pilot burner; also an improved single point ignition system wherein means is provided for extinguishing the intermediate pilot burner means and establishing a flow of fuel to the oven or like burner after a time delay following ignition of the pilot burner for igniting the main burner, and an improved thermoelectric control device and other instrumentalities for accomplishing the new and advantageous results therein set forth.

One of the main objects of the present invention is to provide a simple, improved and effective single point ignition system which will provide all of the advantageous results obtained with the systems disclosed and claimed in my above identified copending application, and in which the gas cock or other gas shut-off means for opening and closing the fuel supply line is the only item requiring actuation manually to secure the desired single point ignition.

Another object of the invention is to provide a single point ignition system in which the main

2

thermoelectric control device (such as a valve) may be located wherever convenient outside the oven or high temperature zone.

Another object of the invention is to provide an improved form of thermoelectric control device for extinguishing the intermediate pilot burner means and establishing a flow of fuel to the oven or like burner after a time delay following ignition of the pilot burner for igniting the main burner; also an improved form of thermoelectric control device which will shut off or prevent the supply of fuel to the oven pilot burner and to the intermediate pilot burner means and oven burner in case the oven or like pilot burner is 15 extinguished or fails to ignite.

Another object of the invention is to provide an improved thermoelectric control device in which a thermocouple or other thermoelectric generator heated by the oven pilot burner is 20 adapted to energize its connected electromagnet sufficiently during the time delay to open the main thermoelectric valve and to hold it open.

Another object of the invention is to provide 25 a single point ignition system and instrumentalities therein, as will hereinafter appear, having various features of novelty and advantages and which are particularly characterized by their 30 simplicity in construction, their economy in manufacture and installation, and their effectiveness in use.

Further objects and advantages of the invention 35 will appear from the following detailed description, taken in connection with the accompanying drawings which illustrate the manner of 40 constructing and operating an illustrative embodiment of the invention.

In the drawings:

Figure 1 is a diagrammatic view showing a 45 single point ignition system embodying the present invention;

Figure 2 is a sectional view taken axially through the thermoelectric control device shown 45 in Figure 1; and

Figure 3 is an axial section taken substantially on the line 3—3 of Figure 2.

Referring now to the drawings, the burner 1 is the baking oven, broiler or other remote burner. It is usually located in the lower part 50 of the range or other appliance.

The pilot burner 2 is the constantly burning pilot burner. It may be, for example, the top pilot burner for the top burners of a gas range or other constantly burning pilot burner. The

pilot burner 2 is usually located in the upper part of the appliance.

A fuel supply pipe 3 leads to the burner 1 for the delivery of gaseous or other fuel thereto, for example, through a mixing chamber 4 to which air is admitted through adjustable air inlets (not shown) as well understood in the art. The flow of gas through the pipe 3 is controlled by a thermoelectric control valve 5 and by a gas cock 6 or other gas shut-off means connected into the pipe 3 anterior of the valve 5 and operable to open and close the fuel line. Where hereinafter, in the specification and in the appended claims, I refer to a gas cock, I intend to include within that terminology the gas cock shown in the drawings and all other gas shut-off means such as a remotely controlled solenoid valve and all other means of shutting off the gas supply.

The oven or like burner 1 is provided with an oven or like pilot burner 7 for igniting it. A flash tube 8 has a laterally turned upper end opening directly to the constantly burning pilot burner 2. This tube extends downwardly and opens at its lower end to an intermediate pilot burner 9. The intermediate pilot burner 9 is spaced laterally from the oven pilot burner 7, and the tube 8 has at its lower end a generally horizontally extending branch 8' which opens at its outer end directly over the flame position 10 of the oven pilot burner 7.

The thermoelectric control device 5 comprises a valve body formed of top and bottom valve body parts 15 and 16 clamped together by screws 17 with a diaphragm 18 therebetween. The valve body part 15 has an inlet 19 and an outlet 20. Contiguous sections of the fuel supply pipe 3 are connected to the inlet 19 and outlet 20, for example, by screwing them into the inlet and outlet which are shown as internally threaded. Internally, the valve body part 15 has a generally L-shaped outlet chamber 21 having a longitudinally extending part in open communication with the outlet 20 and a transversely extending portion defined by a cylindrical wall 22. An inlet chamber 23, in open communication with the inlet 19, terminates at its inner end in a generally annular-shaped portion which embraces the cylindrical wall 22.

The wall 22 terminates in an annular valve seat 24. An armature 25, of disc-like form, has a yielding or other suitable valve or valve facing 26 adapted to seat against the seat 24 to shut off the flow of gas from inlet 19 to outlet 20 through chamber 21. A hood 27 is clamped to the valve body part 15 by a union nut 28, and preferably with a hood gasket 29 therebetween.

In the illustrated embodiment of the invention, the means for operating the valve 26, and more particularly the means for opening this valve, is in the form of an electromagnet comprising a magnet frame or coil spool 30 and a coil 31. One side of the coil 31 is connected by a lead 32 to one of the thermocouple elements 33 of a thermocouple 34 or other suitable thermoelectric generator (such as a thermopile). The other element 35 of the thermocouple 34 is connected by a lead 36 to one contact 37 of a tilting mercury switch 38 (Figure 2) within the valve body part 16. The other and adjacent contact 39 of the switch 38 is connected by a lead 40 to the other side of the coil 31.

The thermocouple 34 and lead connections therefor may be of the general character disclosed and claimed in Oscar J. Leins Patent No. 2,126,564, granted August 9, 1938, or it may be of any other

suitable character, or in the form of a thermopile or other thermoelectric generator. The thermoelectric generator has one or more hot junctions, for example the hot junction 41, which is placed in position to be heated by the flame 42 of the pilot burner 7.

In the illustrated embodiment of the invention, the electromagnet has a flux shell 45 and a spacer ring 46. The lower end of the coil spool 30 has an axial recess, and disposed in this recess and interposed between spool 30 and armature 25 is a coiled spring 47 which operates to move armature 25 to retracted position and to seat the valve 26 on valve seat 24 when the electromagnet is de-energized. Energization of the electromagnet by heating of the hot junction of the thermocouple 34 is sufficient to lift valve 26 to open position against the action of spring 47. A hood spring 48, interposed between the top of the spool 30 and hood 27, seats the shell 45 in the valve body part 15 at 49.

In commercial practice, one of the thermocouple elements, for example the outer tubular thermocouple element 33, may be grounded and, as shown in Figure 3, one side of the coil 31 may be grounded at 50 to the valve body part 15. Also as shown in Figure 3, the lead 40 between the other side of the coil and the mercury switch contact 39 may be connected to a terminal block 51, which, in turn, is connected by connector leads 52 and 53 and wire lead 54 to contact 39. The other contact 37 is shown connected by wire lead 55 to a connector lug 56 which is connected in circuit with a terminal tip 57 having a conical depression in its outer end into contact with which a terminal cone (not shown) on the adjacent end of conductor 36 is adapted to be detachably clamped by a sleeve (not shown) screwed into the threaded socket 58 in the valve body part 16.

The bottom of the valve body part 15 has a recess 60 spaced inwardly from its periphery. Disposed in this recess and above diaphragm 18 is a cover plate 61 clamped to valve body part 15 by screws 61' (Figure 3) with a diaphragm 62 therebetween. A port 63 opens from inlet chamber 23 into chamber 64 above diaphragm 62. Another port 65 opens from inlet chamber 23 into chamber 66 above diaphragm 18.

The valve body part 15 has a pilot outlet passage 67 for supplying fuel to the intermediate pilot burner 9 through a pipe 68 which may be screwed into the pilot outlet 69. Fuel is adapted to be delivered from the diaphragm chamber 64 to the passage 67 through a passage 70, the lower end of which is surrounded by an annular valve seat 71. A valve or valve facing member 72 is adapted to seat against seat 71 to shut off the supply of fuel to the intermediate pilot burner 9. The pilot burner 7 is supplied with fuel by a pipe 73 connected at 74, for example, to the fuel supply pipe 3 between gas cock 6 and the thermoelectric control device 5. The constantly burning pilot burner 2 is supplied with fuel by a pipe 75 connected at 76, for example, to the fuel supply pipe 3 anterior of the gas cock 6.

Valve or valve facing 72, which is of disc-like form, is secured to the diaphragm 62 at the axis thereof by a rivet 78. The diaphragm 62 may have diaphragm plates, and interposed between the bottom of this diaphragm and cover plate 61 is a spring 79. A port 80 opens from the outlet chamber 21 and through port 81 into chamber 82 beneath diaphragm 62.

The mercury bulb 38 of the mercury switch is carried by a bulb holder 85 pivoted at 86 on a bulb

holder bracket 87. The bulb holder 85 has pins 88 which are engaged by the notched lower ends of the depending legs of a diaphragm bracket 89. The diaphragm 18 may have diaphragm plates 90, and bracket 89 is secured to the diaphragm 18 at the axis thereof by a rivet 91. A spring arm 92 is notched at one end at 93 for engagement of pins 88 therein. The other end of arm 92 is notched at 94 for engagement with a pin 95. The pin 95 is carried by a spring arm bracket 96 secured in place by screws 97. A coiled spring 98 is interposed between the arm 92 and the base of bracket 96.

A diaphragm holding ring 100 is secured by screws 101 to the bottom of the interior of valve body part 16, with a diaphragm 102 clamped therebetween. A port 103 opens into the air chamber 104 within valve body part 16 below diaphragm 18. Passage 105, which is adapted for placing chamber 106 beneath diaphragm 102 in communication with port 103, is surrounded at its upper end by an annular valve seat 107. A valve or valve facing member 108 is adapted to seat against seat 107 to shut off communication between chamber 106 and the air chamber 104 within valve body part 16. Valve or valve facing 108, which is of disc-like form, is secured to the diaphragm 102 at the axis thereof by a rivet 109.

A filter cover plate 110 is secured by screws 111 to the bottom of the valve body part 16 with an air filter 112 clamped marginally therebetween. A port 113 (Figure 3) opens from chamber 106 beneath diaphragm 102 into chamber 114 above filter 112. Chamber 115, beneath filter 112, opens to atmosphere through port 116.

For adjustable time delay as will hereinafter appear, the air below diaphragm 18 is prevented from quick escape by an adjustable time delay device in the form of a tapered pin 120 fitted into or cooperating with a tapered bore 121. A port 122 places the interior of chamber 104 beneath diaphragm 18 in communication with bore 121, and a passage 123 places the inner end of the bore 121 in communication with chamber 114 above filter 112.

Although such details may vary widely within the scope of the present invention, the pin 120 is shown screwed at 125 into the valve body part 16, and its outer headed end is shown as provided with a kerf 126 for engagement, for example, by a screw driver or other suitable implement for adjusting the pin 120 to any desired position. The opening through which access to pin 120 is obtained may be closed by a plug 127 screwed into valve body part 16.

The operation of the system shown in the drawings is as follows:

When gas cock 6 is opened gas is admitted to the tops of diaphragms 62 and 18 by means of ports 63 and 65. Valve 72 will open against the pressure of spring 79, and gas will flow to the intermediate pilot 9 through passage 67 and pipe or tube 68. Opening of gas cock 6 also admits gas to pilot burner 7 through pipe or tube 73. The gas from the intermediate and oven pilot burners rises in tube 8, which is always relatively cool to permit this action. As it reaches the flame of constantly burning pilot burner 2 the gas is ignited and then recedes or flashes back to light the intermediate and burner pilot burners 9 and 7. The turning of the upper end of the flash tube laterally toward pilot burner 2 reduces the possibility of extinguishing this pilot burner by flash back action in tube 8.

Thermocouple 33 is now heated and energizes electromagnet 30, 31 which lifts valve 26 and admits gas to the oven burner 1 through outlet 20 and fuel supply pipe 3. A gas pressure is now established on the outlet side of valve 5, and gas will flow through ports 80 and 81 to the under side of diaphragm 62. This neutralizes pressures on opposite sides of diaphragm 62, and valve 72 closes with the help of spring 79, thereby stopping or shutting off the supply of gas to the intermediate pilot burner 9. In the event gas cock 6 is now closed and immediately opened again, it could occur that there would be sufficient power in the electromagnet 30, 31 to keep valve 26 in open position. In such case valve 72 would stay closed, pilot burners 9 and 7 would not ignite, and unburned gas would stream from the oven burner, thereby creating a dangerous hazard.

In order to prevent such occurrence the time delay and switch system functions as follows:

When the gas cock 6 is opened and gas pressure is established above diaphragm 18 through port 65, the air in chamber 104 below this diaphragm is prevented from quick escape by the tapered time delay pin 120. The adjustment of this pin determines the quickness of escape of the air, and thereby the time delay. The delay is timed to assure closing of the valve 26 and thereby shutting off of the fuel supply to the main burner whenever the gas cock 6 is closed even though only momentarily.

The air escapes only slowly as determined by the position of pin 120, and follows the path through ports 122, 123, through air filter 112, and discharging into the atmosphere through port 116. The diaphragm 18 will therefore move only slowly and finally tip mercury bulb 38 in a counterclockwise direction, as viewed in Figure 2, sufficiently to make contact at 37, 39 to complete the electric circuit between the thermocouple or other thermoelectric generator 33 and coil 31.

Whenever the gas cock 6 is closed the diaphragm 18 must return quickly into neutral position so that in case the valve 6 is opened again immediately, the diaphragm 18 will be in uppermost position for a new time delay cycle. The passage (122, 121, 123, 112, and 116) is not suitable for this operation, and the other means comprising the diaphragm 102 has therefore been provided. When the gas cock 6 is closed, gas pressure on the diaphragm 18 is eliminated and spring 98 will endeavor to return the diaphragm 18 into top position, and, in doing so, a suction is created below the diaphragm 18. This suction lifts diaphragm 102 and opens valve 108, which establishes an open or free air passage through port 116 and air filter 112, port 113 (Figure 3), valve seat 107 and port 103 which connects with the air chamber below the diaphragm 18. As shown in dotted lines in Figure 3, port or passage 103 leads to a passage 103' which opens at its upper end into the chamber 104. This air passage is unrestricted and will therefore tend to replace the air quickly.

In operation, the valve 108 must close tightly on the downward stroke of diaphragm 18 so that the time delay may be effective. This tight seal is accomplished by means of the diaphragm 102 whose area is much larger than the valve seat area 107, and therefore exerts correspondingly larger pressure on valve seat 107 to oppose the pressure on the valve seat area directed upwardly.

If desired, the fuel supply pipe 3 may be provided with a thermostat valve 130 connected, for example, by a tube 131 to a thermostat bulb 132 located where it will be subject to the heat of the oven burner 1. In such case the thermostat bulb 132 and its connected thermostat valve 130 serves as a limit device for shutting off the flow of fuel to the burner 1 upon the occurrence of predetermined maximum temperatures. The thermostat may, of course, be adjusted to operate at different temperatures, and I contemplate other forms of thermostats and other forms of thermostatic controls than the one shown in Figure 1 of the drawings, which is for purposes of illustration.

The present invention contemplates many variations in the form and details of the thermostatic control device 5, and many variations in the form of the single point ignition system with which it is shown in the drawings. The embodiment of the invention shown in the drawings is, therefore, for illustrative purposes only, and it is to be expressly understood that the drawings and the accompanying specification are not to be construed as a definition of the limits or scope of the invention, reference being had to the appended claims for that purpose.

I claim:

1. In apparatus of the class described, in combination, a first constantly burning pilot burner, a burner remote from said first pilot burner, a second pilot burner in proximity to said burner for lighting same, a third pilot burner intermediate said first and second pilot burners for assuring ignition of said second pilot burner from said first pilot burner, a fuel supply line for supplying fuel to said burner and said pilot burners, said first, second and third pilot burners each being connected to said fuel supply line to receive fuel therefrom, valve means to open and close said fuel supply line posterior of the fuel supply to said first pilot burner, a first valve member in said fuel supply line on the outlet side of said valve means and posterior of the fuel supply to said second pilot burner, said valve member having an open position or flow of fuel to said burner and closed position shutting off the flow of fuel to said burner, a second valve member in said fuel supply line on the outlet side of said valve means and posterior of the fuel supply to said second pilot burner, said second valve member having means responsive to the pressure of the fuel in said fuel supply line when said valve means is opened and operable by the fuel pressure to open position only when said first valve member is closed for the flow of fuel to said third pilot burner, the pressure responsive means of said second valve member being responsive to equalizing fuel pressure for closing of said second valve member when said first valve member opens.

2. Apparatus according to claim 1 wherein the pressure responsive means of said second valve member comprises a diaphragm subject to the pressure of the fuel in said fuel supply line on the inlet side of said first valve member when said first valve member is closed, and subject to equalizing fuel pressure when said first valve member is open.

3. Apparatus according to claim 1 wherein there is a thermoelectric generator subject to the heat of said second pilot burner and an electromagnet adjacent to said first valve member and connected in circuit with said thermo-

electric generator for operating said first valve member to open position.

4. In apparatus of the class described, in combination, a first constantly burning pilot burner, a burner remote from said pilot burner, a second pilot burner in proximity to said burner for lighting same, a third pilot burner intermediate said first and second pilot burners for assuring ignition of said second pilot burner from said first pilot burner, a fuel supply line having fuel supply connection with said main burner and fuel supply connections with said pilot burners for supplying fuel to said burner and said pilot burners, valve means to open and close said fuel supply line posterior of the fuel supply connection to said first pilot burner, a first valve member in said fuel supply line on the outlet side of said valve means and posterior of the fuel supply connection to said second pilot burner, said valve member having an open position for flow of fuel to said burner and closed position shutting off the flow of fuel to said burner, a second valve member in said fuel supply line on the outlet side of said valve means and posterior of the fuel supply connection to said second pilot burner, said second valve member having means responsive to the pressure of the fuel in said fuel supply line when said valve means is opened and operable by the fuel pressure to open position only when said first valve member is closed for the flow of fuel to said third pilot burner, the pressure responsive means of said second valve member being responsive to equalizing fuel pressure for closing of said second valve member when said first valve member opens, a thermoelectric generator subject to the heat of said second pilot burner, an electromagnet adjacent to said first valve member and connected in circuit with said thermoelectric generator for operating said first valve member to open position, a switch in the circuit for said electromagnet and said thermoelectric generator, and means responsive to the pressure of the fuel in said fuel supply line on the inlet side of said first valve member for actuating said switch to closed position.

5. Apparatus according to claim 4 wherein there is a chamber having a relatively restricted outlet, and wherein the means responsive to the pressure of the fuel in said fuel supply line on the inlet side of said first valve member for actuating said switch to closed position comprises a diaphragm subject on one side to the pressure in said chamber whereby with the restricted outlet for said chamber to provide a time delay in closing said switch following ignition of said second pilot burner.

6. Apparatus according to claim 4 wherein there is a chamber having a relatively restricted outlet, and wherein the means responsive to the pressure of the fuel in said fuel supply line on the inlet side of said first valve member for actuating said switch to closed position comprises a diaphragm subject on one side to the pressure in said chamber whereby with the restricted outlet for said chamber to provide a time delay in closing said switch following ignition of said second pilot burner, there also being means for establishing free admission of air into said chamber when said valve means is closed whereby said diaphragm will quickly actuate said switch to open position.

7. Apparatus according to claim 4 wherein there is a chamber having a relatively restricted outlet, and wherein the means responsive to the

pressure of the fuel in said fuel supply line on the inlet side of said first valve member for actuating said switch to closed position comprises a diaphragm subject on one side to the pressure in said chamber whereby with the restricted outlet from said chamber to provide a time delay in closing said switch following ignition of said second pilot burner, and wherein there is means for adjusting said relatively restricted outlet to adjust the amount of time delay in closing said switch following ignition of said second pilot burner.

8. Apparatus according to claim 4 wherein there is a chamber having a relatively restricted outlet, and wherein the means responsive to the pressure of the fuel in said fuel supply line on the inlet side of said first valve member for actuating said switch to closed position comprises a diaphragm subject on one side to the pressure in said chamber whereby with the restricted outlet from said chamber to provide a time delay in closing said switch following ignition of said second pilot burner and wherein there is spring means for returning said diaphragm to the position which it occupies when said valve means is closed and said switch comprises a tilting mercury switch disposed within said chamber.

9. In a control device of the class described, in combination, a valve body having an inlet for receiving fluid under pressure and a first fluid outlet, a first valve member having closed position shutting off the flow of fluid from said inlet to said first outlet and open position for flow of fluid from said inlet to said first outlet, said valve body having a second fluid outlet, a second valve member having closed position shutting off the flow of fluid from said inlet to said second outlet and open position for flow of fluid from said inlet to said second outlet, means responsive to the pressure of the fluid entering said inlet to open said second valve member when said first valve member is closed and responsive to equalizing fluid pressure for closing of said second valve member when said first valve member opens, an electromagnet adjacent to said first valve member for operating said first valve member to open position, a switch connected in circuit with said electromagnet, and means responsive to the pressure of the fluid on the inlet side of said first valve member for actuating said switch to closed position.

10. A device according to claim 9 wherein there is a chamber having a relatively restricted outlet and wherein the means responsive to the pressure of the fluid on the inlet side of said first valve member for actuating said switch to closed position comprises a diaphragm subject on one side to the pressure in said chamber whereby with the restricted outlet for said chamber to provide a time delay in closing said switch.

11. A device according to claim 9 wherein there is a chamber having a relatively restricted outlet and wherein the means responsive to the pressure of the fluid on the inlet side of said first valve member for actuating said switch to closed position comprises a diaphragm subject on one side to the pressure in said chamber having a relatively restricted outlet whereby with the restricted outlet for said chamber to provide a time delay in closing said switch, there also being

means for establishing free admission of air into said chamber whereby said diaphragm will return quickly to normal position.

12. A device according to claim 9 wherein there is a chamber having a relatively restricted outlet and wherein the means responsive to the pressure of the fluid on the inlet side of said first valve member for actuating said switch to closed position comprises a diaphragm subject on one side to the pressure in said chamber whereby with the restricted outlet for said chamber to provide a time delay in closing said switch, there also being means for adjusting said relatively restricted outlet to adjust the amount of time delay in closing said switch.

13. A device according to claim 9 wherein there is a chamber having a relatively restricted outlet and wherein the means responsive to the pressure of the fluid on the inlet side of said first valve member for actuating said switch to closed position comprises a diaphragm subject on one side to the pressure in said chamber whereby with the restricted outlet for said chamber to provide a time delay in closing said switch, there also being spring means for returning said diaphragm to its normal position and said switch comprises a tilting mercury switch disposed within said chamber.

14. In a control device of the class described, in combination, a valve body having an inlet for receiving fluid under pressure and a first fluid outlet, a first valve member having closed position shutting off the flow of fluid from said inlet to said first outlet and open position for flow of fluid from said inlet to said first outlet, said valve body having a second fluid outlet, a second valve member having closed position shutting off the flow of fluid from said inlet to said second outlet and open position for flow of fluid from said inlet to said second outlet, means responsive to the pressure of the fluid entering said inlet to open said second valve member when said first valve member is closed and responsive to equalizing fluid pressure for closing of said second valve member when said first valve member opens, and means responsive to the pressure of the fluid entering said inlet for producing a time delay after opening of said second valve member before said first valve member opens.

15. A device according to claim 14 wherein there is an electromagnet which, when energized, is adapted to open said first valve member, and wherein there is means responsive to the pressure of the fluid entering said inlet for producing a time delay after opening of said second valve member before said electromagnet is energized.

ERNST WITZEL.
